CARTON AND CARTON BLANK

Arthur Rous, New York, N. Y.

Application April 7, 1944, Serial No. 530,034

4 Claims. (Cl. 229—17)

My invention relates to a new and improved box or carton, and a new and improved blank from which said carton can be assembled, or from which a part of the carton can be assembled.

The principal objects of my invention are to provide a carton which can be made by assembling a suitable flat blank, in order to provide a pouring opening, which has an improved gate or closure. Said blank is optionally a one-piece blank.

Another object of the invention is to provide a carton of this type which can be manufactured at low cost.

Additional objects of the invention will be stated in the annexed description and drawing which illustrate a preferred embodiment thereof.

Fig. 1 is a plan view of a blank which is folded or assembled in order to provide the improved carton. This view is to scale, and reference is made thereto for various details. For convenience, the vertical axis of the blank in Fig. 1, is designated as its longitudinal axis.

Fig. 2 is a perspective view of the pouring end of the carton with the gate in the closed position.

Fig. 3 is a view, similar to Fig. 2, showing the gate in the open position.

Fig. 4 is a sectional view on the line 4—4 of Fig. 2.

Fig. 5 is a sectional view on the line 5—5 of Fig. 3.

Fig. 6 is a sectional view on the line 6—6 of Fig. 2.

The carton comprises an external front wall 14, a rear wall 12, side walls 11 and 13, and an internal front wall or internal front flap 10. These walls 10, 11, 12, 13 and 14 are designated as longitudinal walls. They provide the body of the assembled carton.

In the assembled carton, the external front wall 14 overlies the internal front wall or internal front flap 10. Said walls 14 and 10 are connected to each other by any suitable adhesive, or in any other manner, save for flap 21a.

The internal front wall 10 has a rectangular bottom flap 19 and the external front wall 14 has a rectangular bottom flap 20. In the assembled carton, said bottom flap 20 is located under said bottom flap 19, and said flaps 19 and 20 are connected to each other by any suitable adhesive or the like.

The internal front wall 10 has a rectangular top flap 28 which is provided with an opening 25.

The external front wall 14, which has a free

longitudinal edge, is provided with a curved through-and-through cut c which extends laterally inwardly from said free edge, in order to provide a flap 21a, which is integral with external front wall 14. The free longitudinal edge of said front wall 14 joins an inwardly directed or cut-away edge-portion 22, which extends to said curved cut-line c.

The external front wall 14 has a top flap 26 which is provided with a longitudinal or vertical through-and-through cut C, in order to provide another flap 21. Such flap 21 has an edge portion 21b which is inclined to the longitudinal vertical axis of the blank in Fig. 1. Said flap 21 is the gate or closure of the carton.

The rear wall 12 is provided with a rectangular top flap 27, and with a rectangular bottom flap 29. The side wall 13 is provided with a rectangular top flap 16 and with a rectangular bottom flap 18. The side wall 11 is provided with a rectangular top flap 15 and with a rectangular bottom flap 17.

The flap 15 is provided with an opening 24 which is laterally aligned with the opening 25 of the flap 28 in the flat blank of Fig. 1. Said openings 24 and 25 are of equal diameter. The flap 16 is provided with a pouring opening 23 which is smaller than the perforations 24 and 25.

The blank is scored along the respective lines s and it is cut through and through along the respective cut-lines c.

In order to assemble the carton, the blank is folded along the vertical score lines s of Fig. 1, until the respective external and internal front walls 14 and 10 abut each other, and said front walls 14 and 10 are parallel to the rear wall 12. The side walls 11 and 13 are then parallel to each other. The flaps 19 and 20 are bent inwardly until they are perpendicular to the walls 10 and 14. The flap 20 is located under the flap 19, and these flaps 19 and 20 are connected by adhesive. The flap 29 is bent inwardly. The free edges of said flaps 19, 20 and 29 then abut each other or slightly overlap each other. The flaps 17 and 18 are then bent inwardly, so that the flap 17 is located under flap 18. These flaps 19, 11, 29, 18, and 20 at the bottom end of the box are secured to each other by adhesive, thus permanently closing the bottom end of the box or carton.

The flaps 28 and 27 are then bent inwardly, and the flap 26 is then bent inwardly. Said flap 26 overlies the unperforated part of the flap 28, without overlying the perforation or opening 25. The flap 26 is fixed to the adjacent part of the

The flaps 28 and 27 are then bent inwardly, and the flap 26 is then bent inwardly. Said flap 26 overlies the unperforated part of the flap 28, without overlying the perforation or opening 25. The flap 26 is fixed to the adjacent part of the

flap 28 by adhesive or the like. The gate flap 21 is also bent inwardly, so that said flap 21 closes the opening 25. The flap 15 is then bent inwardly, so that its opening 24 registers with the opening 25 of the flap 28. The gate flap 21 is thus located slidably between the superposed flaps 28 and 15 of the pouring end-wall of the carton.

The flap 16 is then bent inwardly so that its opening 23 is aligned with the aligned openings 24 and 25.

The assembly of the flaps at the top of the box is made by adhesive or in any other suitable manner, so that the flaps 21 and 21a are freely outwardly movable relative to the adjacent flaps and walls of the box.

When the gate-flap 21 is in its closed position, which is shown in Fig. 2, its supporting flap 21a is flush with the external front wall 14. The cut-away edge-portion 22 provides a notch which makes it easy to manipulate the flap 21a.

The perforation 23 is initially closed by a removable closure which is integral with the flap 16. For this purpose, the flap 16 may be provided with a removable disk at the opening 23, so that said disk can be easily removed from the assembled carton. The flap 16 can be scored at the edge of opening 23.

Hence, after the gate-flap 21 has been moved into the open pouring position shown in Fig. 3, the removable disk which initially plugs the outlet opening 23, can be easily removed. For the purposes of the invention, the flap 16 is considered as having a pouring opening, even if said pouring opening is formed after the carton is assembled.

The gate-flap 21 thus provides a movable gate for controlling the dispensing of the contents of the carton, through its pouring opening. The tip of the gate-flap 21 remains located between the respective adjacent end-flaps of the pouring end-wall, when said gate-flap 21 is in its open position. The longitudinal body wall 14 serves as a gate-supporting wall, since the gate-supporting flap 21a is turnably connected to body wall 14. In the blank, said gate-supporting wall 14 has a free longitudinally disposed edge.

The sealing flaps 19, 17, 29, 18, 20 are disposed laterally relative to the longitudinal axis of the blank, at laterally coincident edges of the body walls of the blank.

The flaps 28, 15, 27, 16 and 26 are similarly laterally disposed.

The invention is not limited to a one-piece blank, or to the configuration of the blank and carton which is disclosed as a preferred embodiment.

I claim:

1. A carton which has a body which comprises longitudinal body walls, one of said body walls being a gate-supporting wall, said body having a closed end and a pouring end, said body walls having superposed flaps at said pouring end, said flaps having aligned openings, said gate-supporting wall having a gate-supporting flap turnably connected thereto along a line which is perpendicular to said superposed flaps, said line being located laterally between the longitudinal edges of said gate-supporting wall a gate-flap which is connected to said gate-supporting flap, said gate-flap being slidably located between two of said superposed flaps, said gate flap being slidable in

union with the outward turning movement of said gate-supporting flap to clear said openings, said gate-supporting flap being turnable to a flush position in which it is flush with said gate-supporting wall, said gate being located and dimensioned to close said openings of the flaps between which said gate is located, when said gate-supporting flap is in said flush position.

2. A carton-blank, said blank having a longitudinal axis, said blank having longitudinal body walls which are bendable relative to each other to provide the body of said carton, said body walls having aligned lateral edges in said blank, said lateral edges being perpendicular to said longitudinal edges, said blank having end-flaps which are bendably connected to said body walls at said aligned lateral edges, at least some of said end flaps being dimensioned to be located in overlying relation when said end flaps are bent inwardly relative to said body walls, said end flaps providing an end wall for the body of the carton when said end flaps are thus inwardly bent, the end flaps which can thus be located in said overlying relation having openings which are located in registration when said end flaps are thus inwardly bent, one of said body-walls having a free longitudinal edge, said last-mentioned body wall being a gate-supporting wall, said gate-supporting wall being cut laterally inwardly from its free edge to provide a gate-supporting flap, said gate-supporting flap being turnable relative to said gate-supporting wall on a longitudinal hinge line which is located laterally between the longitudinal edges of said gate-supporting wall, the end-flap which is connected to said gate-supporting wall being cut along a longitudinal cut-line which is coincident with said hinge-line to provide a gate, said gate being dimensioned to close said openings in the assembled carton when said gate-supporting flap is flush with the gate-supporting wall in the assembled carton.

3. A carton which has a body which comprises body walls, said body having a longitudinal axis, means for sealing one end of said body, said body walls having superposed end flaps at the other end of said body, said superposed flaps having aligned perforations so that said other end is the pouring end-wall of said carton, one of said body walls being a gate-supporting wall, said gate-supporting wall being laterally inwardly cut to provide a gate-supporting member, said gate-supporting member being turnable relative to said gate-supporting wall along a longitudinal line which is located laterally between the longitudinal edges of said gate-supporting wall, the respective flap of said gate-supporting wall at said pouring end-wall being cut longitudinally intermediate its edges to provide a gate which is integral with said gate-supporting member and also to provide a portion of said last-mentioned flap to which said gate is relatively movable, said gate being slidably located between two of said perforated flaps, said portion being adhesively connected to the perforated end flap which is directly under said portion.

4. A carton according to claim 3, in which said portion is also adhesively connected to the next overlying perforated flap, there being at least one additional perforated flap which is adhesively connected to said next overlying perforated flap.

ARTHUR ROUS.
